United States Patent Office

Des. 196,247
Patented Sept. 10, 1963

196,247

TUMBLER OR LIKE ARTICLE

Freda Diamond, New York, N.Y., assignor to Owens-Illinois Glass Company, Toledo, Ohio, a corporation of Ohio

Filed Dec. 11, 1962, Ser. No. 72,811

Term of patent 3½ years

(Cl. D36—8)

I claim:

The ornamental design for a tumbler or the like, substantially as shown and described.
